2,531,743

METHOD OF FILLING FLEXIBLE CONTAINERS WITH FINELY DIVIDED MATERIALS AND MACHINE THEREFOR

Don Ray, Beverly Hills, Calif.

Application September 14, 1945, Serial No. 616,298

9 Claims. (Cl. 226—59)

1

This invention relates to improvements in the art of packaging finely divided materials and particularly pulverulent materials such as, for example, powdered milk, chocolate, cocoa, prepared flours, lampblack, cornstarch, powdered sugar, finely ground pharmaceuticals such as powdered licorice, etc. The invention relates to a method of procedure whereby predetermined quantities of such finely divided materials may be placed into containers in a rapid manner without the creation of unpleasant and sometimes dangerous dusts. The invention also relates to a simple and effective mechanism whereby such finely divided materials may be placed into containers.

Lampblack, powdered milk and other very finely divided materials are packaged with difficulty because of the tremendous quantities of air adsorbed by each of the particles and contained between the particles. The movement of any volume of such finely divided material creates a cloud of dust. As a result, the operation is disagreeable to the operators and often gives rise to high losses and to dangerous dust problems since many of these dusts are of an explosive character. In addition, many of these finely divided materials are light in weight and very bulky. When placed into flexible bags, the volumetric capacity of the bag is not utilized to best advantage. A resort has been made to vibration of the package or container during the filling operation in an attempt to pack the pulverulent material into a smaller volume but such methods have not been satisfactory and in most instances aggravate losses and the formation of dusts.

The present invention employs a novel mode of operation which, generally stated, comprises supporting an open container within a chamber, reducing the pressure within and around the container simultaneously to a subatmospheric pressure, then isolating the interior of the container from the rest of the chamber, admitting the finely divided material into the container while such interior is isolated from the rest of the chamber, and eventually restoring pressure within the chamber to atmospheric and placing the filled container in communication with such chamber. In this manner the pulverulent or finely divided material may be admitted to a container which is under vacuum so that the vacuum within the container draws a desired amount of the material into the container. By conducting the operation in the manner stated, flexible or collapsible bags may be employed. The finely divided material does not come in contact with the atmosphere until the container has been filled. Definite pres-

2

sure is utilized (in certain forms of the invention) for moving the material into the container and in compressing or compacting the material within the container.

5 The invention, as previously stated, is also directed to a simple and efficient apparatus by means of which the packaging operation may be readily carried out.

It is an object of the present invention, therefore, to provide an improved method of packaging finely divided material without the creation of dusts and accompanying losses.

A further object of the invention is to provide a method of packaging by means of which flexible bags and other containers may be filled under vacuum or at a subatmospheric pressure.

A still further object of the invention is to permit the packaging of finely divided pulverulent material in containers provided with heat and pressure-sensitive inner surfaces so that the filled containers may be rapidly and efficiently sealed, the method preventing the adherence of finely divided materials to the sealed areas of the bag, such dust or particles ordinarily rendering such areas ineffective in subsequent sealing operations.

Again, an object of the invention is to provide a novel combination of elements whereby finely divided materials may be easily packaged.

A still further object of the invention is to provide a packaging machine capable of handling finely divided materials.

These and other objects will become apparent to those skilled in the art from the following description. In order to facilitate understanding, 35 an exemplary form of apparatus is shown on the appended drawings.

In such drawings:

Fig. 1 is a side elevation of one form of device.

Fig. 2 is an enlarged vertical section through 40 the housing of the device with actuating mechanism in elevation.

Fig. 3 is a horizontal section along the plane III—III of Fig. 2.

Fig. 4 is a horizontal section along plane IV—IV 45 of Fig. 2.

Fig. 5 is a vertical section along the plane V—V of Fig. 2.

Fig. 6 is a horizontal section along plane VI—VI of Fig. 2.

50 The simple form of device shown in these drawings comprises a housing 1 which may have transparent front and rear walls 2 and 3, in order to permit observation of the packaging operation.

The housing is preferably provided with an open bottom (a bottom port being indicated at 4),

such bottom being capable of cooperating with a suitable movable closure including means for supporting a container with access of air there-around.

The movable closure may take the form illustrated and comprise a closure plate 5 capable of firmly seating around the open bottom of the housing 1 to form a virtually gas-tight seal therewith. The closure plate may be provided with a recess portion or depression portion 6 adapted to loosely receive the container 7 to be filled. The inner walls of the recess portion may be provided with a plurality of ridges for the purpose of admitting air around the entire container 7, such ridges being indicated in Fig. 6 at 8 and 9. Suitable gasketing means may be carried either by the closure plate 5 or the bottom of the housing 1 so as to make certain that a virtually gas-tight seal is attained when the closure is brought into contact with the bottom of the housing. Any suitable means may be used in moving the closure into operative relation with the housing. Such means may comprise a suitably controlled, vertically movable lifter 10 (shown in Figs. 1 and 5). Such lifter also functions to properly center and guide the upper portion of the container 7 into operative relation with the mechanism within the housing.

The top 11 of the housing carries a feeding tube 12 which extends downwardly into the housing. The upper end of this tube 12 is connected in any suitable manner to a supply of finely divided or pulverulent material which it is desired to package. In Fig. 1 the feeding tube is shown connected to the bottom of a hopper 13, the connection being made by means of a hopper block 14.

As best shown in Figs. 2 and 5, the lower end of the feeding tube 12 is provided with a form block 15, the form block being adapted to loosely fit into the upper part of the container to be filled. In the form shown, the form block is provided with concave and convex container-contacting surfaces 16 and 16', such surfaces presenting a perimeter equal to the perimeter of the internal surface of the opening into the container 7. It may be assumed for purposes of example, that the container 7 is a flexible, foldable bag made of paper, fibrous material, sheet nylon, paper coated with a thermoplastic coating, thin metal foil, cellophane, or various laminates. It may also be noted that the upper portion of the bag 7 extends above the supporting plate 5 so that when such plate is brought into seating engagement with the bottom of the housing 1, the upper portion of the bag encircles the form block 15. Lower edges of the form block may be tapered as indicated at 15' in order to facilitate entry of the form block into the bag.

The feeding tube 12 is provided with an obturator by means of which the flow of material through the feeding tube may be controlled. Preferably such valve is located in the form block 15 and may take the form of a small shut-off valve 17 mounted upon a rotatable pin or shaft 18 extending through the form block, the valve being movable in a recess 19 formed in the lower face of the form block.

The valve 17 may be actuated by means of a lever 20 carried by the post 18, the lever 20 being pivotally connected as by link 21 with an arm 22 mounted upon a valve-actuating shaft 23 extending upwardly through the top of the housing, the upper end of such valve-actuating shaft being provided with the operating handle 24.

The feeder tube 12 may carry a sleeve 25 supporting a spider 26, the spider having radially extending lugs such as 27 adapted to pivotally support clamping arms 28, 29, 30 and the like. The lower ends of such arms are preferably provided with yieldable pads 31, 32, etc., adapted to clamp the upper portion of the bag 7 against the form block 15. The pads 31, 32 and the like preferably conform to the concave portions of the outer surface of the form block.

The upper end of each of the clamp arms 28, 29, 30, is provided with an upstanding cam-contacting finger 34, 35, 36, etc., such fingers being yieldably urged together or toward the feeder tube 12 by means of a continuous coiled spring or O ring 37 positioned within suitable notches or recesses formed in the outer surfaces of such fingers. In order to limit the inward movement of these fingers, a stop collar 38 may be carried by an upward extension of the spider 26.

Slidably mounted upon the tube 12 is a cam block 40 provided with a conical external face against which the ends of the fingers 34, 35, 36 may rest. Upward movement of the cam block 40 is resisted by means of a cam stop nut 41 adjustably positioned upon the feeder tube. The cam block 40 is normally urged against the stop nut 41 by means of a spring 42 bearing against the spider 26 and upwardly against the cam block. As best shown in Fig. 5, the spring 42 may be partly retained within a recess formed in the lower portion of the cam block.

It will be evident from the description given that downward movement of the cam block will cause the fingers 34, 35 and 36 to move outwardly along the conical face of the cam block, thereby pivoting the clamp arms 28, 29 and 30 and bringing the pads 31, 32 and the like in pressure contact against the upper portions of a container extending between the pads and the form block.

Downward motion of the cam block 40 may be imparted in any desired controllable manner. In the example given an operating handle 43 is shown pivoted upon a stud bolt 44 fastened in the side of the housing. The lower end of the operating handle 43 is provided with a cam 45 adapted to bear upon a lever 46 carried by a shaft 47, the shaft 47 being provided with a pair of cam-actuating arms 48 and 49 adapted to contact the upper portion of the cam block 40 and move the cam block downwardly.

The housing is also provided with means for controllably connecting the housing with a source of suction. Such means may comprise a suitable port and a conduit 50 connected thereto. The conduit may include a three-way valve 51 by means of which the conduit may be selectively connected either with a source of suction or with the atmosphere.

The apparatus described hereinabove may be utilized in performing the method of this invention as follows:

A suitable container (such as the bag 7) is placed within the recess 6 of the supporting plate 5 and moved against the bottom of the housing 1 so as to form a tight seal therewith. The upper portion of the bag 7 will be guided by the tapers 15' around the form blocks.

It will be understood that bags of different length but of the same cross-sectional size may be used, a suitable filler block being then inserted into the bottom of the recess 6 so as to make certain that a proper length of bag extends

above the plate 5 and between the form block and the clamping pads 31, 32 and the like.

As soon as the supporting plate 5 is brought into contact with the bottom of the chamber 1, valve 51 may be turned to place the chamber in communication with a source of suction, thereby reducing the pressure within and around the container 7 to a desired uniform subatmospheric pressure. The entire interior of the housing will be reduced to such subatmospheric pressure; but it is important that both the interior and the exterior of the bag 7 be subjected to such low pressure. The indentations or concave surfaces of the filler block 15 assure communication between the interior of the bag and the atmosphere externally of the bag within the housing.

After the desired vacuum has been thus created, both within and without the bag, the interior of the bag is isolated from the rest of the chamber by actuating the handle 43, thereby causing cam block 40 to move downwardly against spring 42 to firmly clamp the upper portions of the bag 7 against the form block. When the bag is caused to cling to the concave portions 16 of the form block, other wall areas of the bag will be stretched taut against the convex portions 18' of the form block.

Finely divided material may then be admitted into the bag 7 by opening the valve 17. This valve is opened by means of actuating handle 24, valve actuating shaft 23, arm 22, link 21, arm 19 and valve post 18. Finely divided or pulverulent material will thus be admitted through the feeder tube 12 directly into the bag 7. Since a subatmospheric pressure exists within the bag 7, the finely divided material will move downwardly through the filler tube 12 and completely fill the bag, that is, fill the bag up to the level of the form block.

At this point it may be noted that the supply hopper 13 may be open to the atmosphere so that the supply of finely divided material in such hopper is subjected to atmospheric pressure at the top. It may be stated, therefore, that the differential in pressure between the hopper 13 and the interior of bag 7 facilitates filling of the bag.

In some instances it may be highly desirable to partly deaerate the finely divided material before it is admitted into the bag 7. The hopper 13 may be supplied with finely divided material from still another hopper through a suitable valved outlet and the hopper 13 may be connected with a source of suction sufficient to partly deaerate the finely divided material in the hopper 13 and to create an absolute pressure in such hopper slightly higher than that in the bag immediately prior to the filling operation.

Moreover, when materials capable of bridging are being packed, a stirring rod or a shaft provided with stirring arms or even an auger may be rotatably mounted axially of the feeder tube 12 so as to facilitate the movement of material through the feeder tube, such stirring rod or auger being preferably only driven when the valve 17 is open.

After the bag has been filled in the manner described above, pressure within the chamber is restored to normal by adjusting the valve 51 so as to place the chamber in communication with the atmosphere. In most instances it will be found that such air pressure acting upon the outside of bag 7 will compact the material therein to some extent. After the chamber has been thus

placed in communication with the atmosphere, the clamp arms 28, 29, 30 are released (as by returning the operating handle 43 to its normal position), thereby permitting atmospheric pressure to act upon the surface of the finely divided material within the bag 7. The filled bag may then be removed from the chamber by permitting the closure plate 5 to drop, whereupon the bag may be immediately subjected to a sealing operation while still supported by the closure member 5, or it may be withdrawn from the closure member and subjected to the action of a separate sealing apparatus.

It may be noted that insasmuch as the bottom of the form block 15 is substantially in the same plane as the bottom of the chamber 1, the finely divided material will be found to have filled the bag substantially to the level of the upper surface of closure member 5, as indicated by the line 52. Moreover, in the event the bag 7 is provided with a thermosealing inner surface or layer, the upstanding upper portion of the bag may be readily folded and sealed so that the contents are not subjected to the action of air for any appreciable length of time.

It has been repeatedly found that it is virtually impossible to obtain a hermetic seal to the open end of a bag if there is any dust on the sealing surfaces of the bag. The minute dust particles appear to keep the two surfaces from complete contact and instead set up channels between the surfaces through which air may readily pass. Bags filled in accordance with the present invention, however, have dust-free surfaces since the sealing surfaces of the bag are in contact with the form block 15 during the entire filling operation and that is the only time during which any dust may exist within the apparatus or within the bag.

It will be quite evident to those skilled in the art that the various operations may be carried out in an automatic sequential manner. The movement of the closure member 5 into contact with the bottom of the housing 1 may automatically cause valve 51 to place the chamber into communication with a source of suction and after a predetermined vacuum has been created within the bag, vacuum-actuated cylinders may cause the clamping arms to operate and the feeding valve 17 to open in proper sequence. Electromagnetic or hydraulic means may also be utilized in carrying out the various operations in their proper order. The entire chamber may be purged with nitrogen or other inert gas; the feeding hopper 13 may also be purged with a similar inert gas in the event the product being handled is readily oxidizable and benefits from pretreatment with nitrogen or some other gas.

Although specific reference has been made to the filling of a flexible, collapsible bag in the example, it is to be understood that the method may be employed in packaging finely divided materials not only in bags but in various other containers such as cylindrical cartons, rectangular cartons with circular openings, etc.

These and other changes and modifications are contemplated and are embraced by the appended claims.

I claim:

1. A machine for filling containers with finely divided materials comprising: a housing having an open bottom; a removable closure for the bottom of the housing, said closure including means for supporting a container with access of air theretaround; a feeding tube positioned in the

house and extending through the top thereof; a form block carried by the lower end of the feeding tube, the form block being adapted to loosely fit the upper part of a container to be filled; resilient clamping elements within the housing controllably movable to clamp the upper edge areas of a container to the form block; an obturating member for the feeding tube; and means for controllably connecting the housing with a source of suction.

2. In a machine for filling containers with finely divided materials, the combination of: a housing having an open bottom; a removable closure for the bottom of the housing, said closure including means for supporting a container to be filled; a feeding tube positioned in the housing and extending through the top thereof; a form block carried by the lower end of the feeding tube, the form block being adapted to loosely fit the upper part of a container to be filled; resilient clamping elements controllably movable to clamp the upper edge areas of a container to the form block; an obturating member for the feeding tube; and means for controllably connecting the housing with a source of suction.

3. In an apparatus of the character stated in claim 2, said form block being provided with concave and convex container-contacting surfaces substantially parallel to the walls of the container and presenting a perimeter equal to the perimeter of the internal surface of the opening into the container.

4. In a filling machine, the combination of: a filling conduit associated with a supply of finely divided material, a form block carried by the end of the filling conduit, said form block being insertable into the opening of a container, said form block being provided with alternate concave and convex container-contacting surfaces substantially parallel to the walls of a container and presenting a perimeter equal to the perimeter of the internal surface of the opening into the container, movable valve means for controllably opening and closing the end of said conduit, and clamping means adapted to releasably hold the container against said form block.

5. A machine for filling containers with finely divided materials comprising: a housing, a removable closure for said housing, said closure including means for supporting a container, a feeding conduit positioned in the housing, a form block carried by the lower end of the feeding conduit, the form block being adapted to loosely fit the upper part of a container to be filled, clamping means adapted to releasably and resiliently hold the container against said form block, and a single means for controllably connecting the housing with a source of suction to generate a uniform sub-atmospheric pressure within the housing and container supported therein before said clamping means resiliently press the upper areas of the container against the form block.

6. In an apparatus of the character stated in

claim 5, the provision of a movable valve for controllably opening and closing the end of the feeding conduit.

7. A method of filling flexible containers with finely divided material comprising: supporting an open flexible container within a chamber; reducing the pressure within and around the container simultaneously to a substantially uniform, predetermined, sub-atmospheric pressure engaging external portions of walls of the container below the open end thereof and pressing opposed engaged portions of said walls inwardly toward each other to isolate the interior of the container from the rest of the chamber; admitting finely divided material into the container while the interior of the container is isolated from the rest of the chamber; then restoring pressure within the chamber to atmospheric and placing the filled container in communication with the chamber.

8. In a filling machine, the combination of: a filling conduit associated with a supply of finely divided material; a form block carried by the end of the filling conduit, said form block being insertable into the opening of a container, said form block being provided with parallel outer walls including alternate concave and convex container-contacting surfaces presenting a perimeter equal to the perimeter of the internal surface of the opening into the container; and movable valve means for controllably opening and closing the end of said conduit.

9. A method of filling flexible containers with finely divided material comprising: supporting an open flexible container within a chamber; holding the flexible container in open position while maintaining communication between the chamber and the interior of the container; reducing the pressure within and around the container simultaneously to a substantially uniform, predetermined, sub-atmospheric pressure, engaging external portions of walls of the container below the open end thereof and pressing the engaged portions of opposed walls inwardly toward each other into concave configuration to isolate the interior of the container from the rest of the chamber; admitting finely divided material into the container while the interior of the container is isolated from the rest of the chamber; then restoring pressure within the chamber to atmospheric and placing the filled container in communication with the chamber.
